UNITED STATES PATENT OFFICE

136,157

DESIGN FOR A SAFETY RAZOR HONE CASE

Lee Roy Scott, Greenwood, Miss.

Application May 24, 1943, Serial No. 110,267

Term of patent 7 years

To all whom it may concern:

Be it known that I, Lee Roy Scott, a citizen of the United States, residing at Greenwood, in the county of Leflore and State of Mississippi, have invented a new, original, and ornamental Design for a Safety Razor Hone Case, of which the following is a specification, reference being had to the accompanying drawings, forming part thereof.

Figure 1 is a side elevational view of a safety razor hone case showing my new design.

Figure 2 is a top plan view.

Figure 3 is an end elevational view.

Figure 4 is a top plan view with the top removed.

Figure 5 is a longitudinal sectional view taken substantially on the line 5—5 of Figure 2.

Figure 6 is a vertical sectional view taken substantially on the line 6—6 of Figure 1.

I claim:

The ornamental design for a safety razor hone case, as shown and described.

LEE ROY SCOTT.
